(57) **CLAIM**

The ornamental design for an electronic camera, as shown and described.

DESCRIPTION

FIG. 1 is a top, front and side perspective view of an electronic camera showing my new design;

FIG. 2 is a front elevational view thereof;

FIG. 3 is a top plan view thereof;

FIG. 4 is a side elevational view thereof from the right of FIG. 2;

FIG. 5 is a bottom plan view thereof; and,

FIG. 6 is a view similar to FIG. 1, but with the parts in a different position.

The material shown in broken line illustrates a possible environment in which the present invention may be found, but forms no part of the claimed design.
